UNITED STATES PATENT OFFICE.

NATHANIEL G. WARTH, OF COLUMBUS, OHIO.

TELEPHONE REPEATER SYSTEM.

978,083.

Specification of Letters Patent.

Patented Dec. 6, 1910.

Application filed July 15, 1907. Serial No. 383,883.

To all whom it may concern:

Be it known that I, NATHANIEL G. WARTH, a citizen of the United States, residing at Columbus, in the county of Franklin and 5 State of Ohio, have invented a certain new and useful Improvement in Telephone Repeater Systems, of which the following is a specification.

The object of the invention is to provide a 10 system of circuits and associated automatically reciprocating repeater apparatus of simplified, efficient and economical character for long distance or difficult transmission heretofore impossible with original transmission, whereby an enfeebled or attenuated initial or repeated telephonic current may be reproduced and retransmitted with increased power by the intermediate station repeaters of a line circuit and thus obtaining 15 a duplication at the distant receiver of the originating actuating sounds with the accuracy and volume usual with single direct transmission.

This invention is directed more specifically to the type of apparatus and arrangement of circuits wherein two repeater instrumentalities are used co-operatively and reciprocally as a "repeater" at each repeating point on a circuit, and the transmission 20 for each telephonic impulse is wholly progressive or unidirectional, and not divided or bidirectional from the repeaters. Repeating systems of the divided or bidirectional transmission class as at present in commercial use are deficient for transmission requiring 25 two or more retransmissions. In the two-way or bidirectional retransmission, of the prior art, the first repeater, when two are connected in a line, (each repeater embracing 30 a single repeater apparatus) is caused to be operated by the backward current as it is by the original currents, which produces a mere confusion of inarticulate sounds and precludes such extra-long range 35 transmission or service as is herein contemplated. The unidirectional transmission secured in my system is produced by the first repeater, that is, the repeater nearest the then-transmitting station, relaying the 40 effects into the associated circuit only and the second repeater relaying those effects into its next associated circuit only, thence to the then-receiving station or telephone or 45 to a similarly operating repeater in the circuit and then to the terminal telephone. The well-known natural flattening or dis-

tortion of the form of the wave due to circuit retarding effects and losses prevents, of course, in practice, a considerable number of retransmissions, but as several retransmissions are necessary or desirable my system makes feasible the extension of retransmission by plural repeating stations.

The operation of my repeaters is such that each individual repeater instrument at each 50 repeater station receives the weakened initial currents from its respective line or circuit section, reproduces the currents with exactness and augmented volume and retransmits them into the associated line circuit with 55 the full energy set up by the transmitter. Each repeater comprises a receiver and a transmitter assembled in repeater relation and both elements are included in local circuits in inductive relation to the line circuits. Each receiver, in addition to actuating 60 its transmitter to send currents into the associated line circuit, has means within its local circuit to avoid any actuation of its transmitter by currents set up locally by 65 either repeater, thereby preventing self-action. This seeming paradoxical condition of the receivers being sensitive to currents induced from the line yet insensitive to the local currents consequently set up, is produced by the circuit arrangement and association of the apparatus, wherein each receiver is subject to the action of two electrically or inductively balanced local circuits 70 in which the magnetic or inductive action 75 effects are counter-balanced or made neutral 80 and are also unbalanced and effective to 85 actuate the transmitters.

The unbalanced effect is made possible by directing the received currents so that they 90 will cooperate in their inductive effect upon the receiver windings, while the neutral or counter-balanced effect is produced by directing the renewed currents so they will 95 flow or act differentially in the balanced 100 local circuits and windings controlling the receivers. The renewed currents when operating to create the neutral effect for the 105 receivers are directed to inductively and co-operatively act upon induction coil secondary windings in the line circuits. A more detailed description of the local effects and actions involved will follow in explaining Figures 1 and 2. The purpose of placing the 110 receivers in local circuits is to maintain the necessary balances, as explained above, and maintain them in a state independent of the

main circuits, whereas in all repeater systems in which the "balance" against the reproduced currents is located in the line circuits are deficient because an unbalanced condition within a main circuit section or between the circuit sections will produce the self-action resulting in the continuous sound termed "howling".

In this system a high state of efficiency is attained by utilizing all induction and balancing coils as active and effective factors in adding to the induced retransmitted currents or to the induced effects upon the receivers. Hence there is no dissipation of current or loss in effect in mere resistances, inductances and capacities, or in derived or artificial circuits as required and used only for balancing local or main circuits of various kinds in the other systems.

The specific improvements in the above enumerated circuits and apparatus will be best understood by a description of the accompanying drawings, but the invention is not limited to the precise details of construction and arrangement shown.

In said drawings—Fig. 1 is a diagram of the line and local circuits connecting the twin repeaters and auxiliary apparatus together for unidirectional transmission. This view shows the line and local circuits divided or separated into their component sections by bridges, thus creating for each an electrical separation as distinctive circuits yet permitting them to be physically joined for economy in wiring or in being connected up for composite service. The primary or transmitter circuits are also bridged together, the bridge connection embracing a battery common to the two transmitters; Fig. 2 is a diagram of a modified form of the arrangement of circuits and apparatus shown in Fig. 1, the line and local receiver circuits being shown physically separated, each receiver circuit controlling a respective receiver winding, whereas, in Fig. 1 both receiver circuits operate the receiver windings in common. The primary circuits of the modified arrangement are also physically separated, each circuit being provided with an individual battery or current supply.

Referring particularly to Fig. 1, which is the preferred embodiment of the system, L and L² designate the line or main circuit sections, and as all the repeater apparatus and circuits proper are shown in the view, the equipping of the main circuit conductors W, W² and W³, W⁴ with cords, plugs and auxiliary switching appliances would at once constitute the arrangement a repeater within a cord-circuit. The line circuit sections are divided and made distinctive by the bridge conductor H. In the main circuit conductors W, W², W³ and W⁴ are included the secondary windings C, C², C³ and C⁴ respectively, of a composite induction

coil, or each such division may be the secondary winding of a small induction coil.

R designates a repeater device composed of an electro-magnetic receiver T and a variable resistance transmitter M, said repeater device being associated by means of third or tertiary windings with the secondary windings C and C², which are identified with the line circuit section L. These tertiary windings are connected in a local or tertiary circuit P², in which circuit is also included the winding or windings of receiver T. An auxiliary or balancing tertiary circuit P is likewise connected in circuit with the receiver, and included in this circuit P with the receiver is the secondary winding of an auxiliary induction coil C⁵. The function of this coil is two-fold. First, to create one-half of an induction or an electrical balance to prevent the receiver T from actuating its transmitter M when currents are being transmitted into circuit section L, and second, to coöperate with tertiary windings C and C² for inward induced currents from circuit section L to operate the repeater R. The two tertiary circuits, or, considering them jointly, the two halves of the receiver circuit, are separated and made distinctive by the bridge connection H² in which the winding of receiver T is included.

The associated repeater R² is likewise composed of a receiver designated T² and a transmitter designated M², and is associated with its particular circuit section L² by means of third or tertiary windings, through the secondary windings C³ and C⁴. Likewise these tertiary windings are connected in a local circuit or half circuit P³ with the receiver T². Also, as in the opposite side, an auxiliary or balancing tertiary circuit P⁴ is connected in circuit with the receiver, and also in this circuit or half circuit is included the secondary winding of an auxiliary induction coil C⁶. The functions of coil C⁶ are identical with those of induction coil C⁵, that is, it sets up in its circuit P⁴ currents that balance those in its twin local circuit P³ and creates an electrical or induction balance for preventing the receiver T² from actuating its transmitter M² when reproduced currents are being transmitted into circuit section L², and coil C⁶ also coöperates with tertiary windings C³ and C⁴ in response to inward induced currents from circuit section L² to operate the repeater R². The two tertiary circuits P³ and P⁴, as in the opposite side, are made distinctive by the separating bridge connection H³ in which the winding of receiver T² is included.

The transmitters M and M² of both the twin repeaters are each included in a primary circuit, which circuits are distinct from the receiver local circuits. In Fig. 1 these two primary circuits, their transmitters and their induction coil primary windings are

associated with a battery B, which is common to both primary circuits. This battery should be of low internal resistance and possess sufficient electro-motive force and quantity to meet the demands of both transmitter circuits in their parallel relationship. The transmitter M is connected in the primary circuit designated B³ and the transmitter M² is connected in the primary circuit 10 designated B². In the circuit B³ are the primary windings of induction coils C³, C⁴ and C⁶ and also inductance coil I², all in series relation. In the circuit B² are likewise connected the primary windings of induction coils C¹, C² and C⁵ and the inductance coil I. The function of the inductance coils I and I² is to prevent reaction or cross-talk between the two primary circuits by reason of their common battery physical association 20 and also to regulate the common battery current supply.

The circuits may be traced and the operation described as follows: The arrows indicate the different currents and the direction 25 of the current flows. The slender solid arrows designate the initial line currents to be reproduced. The heavy solid arrows designate the constant direction of the primary currents set up by the common battery in each primary circuit. These latter arrows also indicate the direction of one phase of an inward induced current when set up in the primary circuits by the line circuit secondary windings. An inward initial line 30 current or impulse in circuit section or line L¹, traverses conductor W³ from right to left, terminates at bridge conductor H, and returns to the originating instrument by way of conductor W¹. This impulse in traversing the secondary windings C³ and C⁴ in the circuit sets up induced currents in the associated primary and tertiary windings, as indicated by the arrows for local circuits P³, P⁴ and B³. In the primary circuit B³ 40 both the battery current and the induced current are shown, in this instance, as flowing in the same direction, by the solid heavy arrows. It will be noted that the receiver T² of repeater R² will be energized by co-operating current flows in both tertiary circuits, and that the tertiary windings C³ and C⁴ coöperate in circuit P³. The reinduced current in circuit P⁴, which is first induced by the secondary windings of coils C³ and C⁴ 45 acting coöperatively to induce into circuit B³, is reinduced, setting up a current in circuit P⁴, which current coöperates with the current in circuit P³ and reinforces the effect in energizing receiver T². A current of opposite phase will produce like effects but of reverse direction in current flows. The action of the superposed induced currents over the primary battery currents 50 upon the coil C⁶ will be regular in effect, as the action in the coil is merely one of

varying the magnetic lines of force or flux lines from the then-existing state due to the field produced by the battery. All the induction coils are in a similar magnetic condition produced by the same battery current. Care, of course, is to be exercised in this connection and in relation to the setting up of the outward inductive effects in the transmitter circuits not to have the induction coil cores too strongly magnetized by 70 the battery. The variation in the existing magnetic state is not effective with a saturated or densely magnetized core, for the reason that both the induced currents and the transmitter currents, especially the former, are incapable of effecting any great variation of a very strong residual field, and any variation produced in the flux lines would not at any time carry the magnetization much, if any, below the point of saturation. Hence the actions in both respects will be more efficient and sensitive when the battery is not sufficient to set up a saturated magnetization of the induction coil cores. 85

The coöperation of the currents set up, as 90 shown, by the three induction coil windings in circuits P³ and P⁴ results in a very effective action in the repeater. The actuation of transmitter M² in this manner sets up a current in its primary windings which 95 are inductively associated with the opposite or L line circuit section. The flow of this current is traceable as follows: from the positive pole of battery B through bus conductor X to the right, through inductance 100 coil I, primary of induction coil C, primary of induction coil C⁵, primary of induction coil C², transmitter M², bus conductor N, to the negative pole of the battery. This primary reproduced current induces a current 105 in the associated main and local circuits. The current induced into the line section L is a reinforced duplicate of the initial current received from line section L² and is thus retransmitted to the receiving instrument or 110 station or to another intermediate repeater. The current induced into the tertiary circuits P and P² through the tertiary windings C, C² and the counter current in secondary winding of coil C⁵, is to create in 115 those circuits for receiver T of repeater R an inactive state by differential current flows. The current induced into the two windings associated with the primary windings of coils C and C² is opposite in direction to the 120 flow in the primaries. These induced currents are designated by the broken arrows shown in connection with line circuit L and tertiary circuits P and P². The current induced into line circuit L is from left to right 125 in conductor W, terminating at bridge conductor H and traversing conductor W² to the next station. The arrangement of the induction coil windings for both repeater tertiary circuits is such that the inductive 130

currents in the two circuits, namely, P with relation to P^2 , and P^3 with relation to P^4 , are respectively alike or of equivalent value. Thus the induced current in P^2 from the coils C , C^2 , taken jointly, is, in amount, the equivalent of the induced current from coil C^5 . Hence the currents in the two circuits, being caused to flow differentially, an equalized and neutral effect is produced for the receiver T . The several windings are similar to those described in connection with repeater R^2 , but as the inducing current in this instance is in the primary circuit B^2 , the flow in the secondary and tertiary windings of the line coils is the same in direction, and the flows in the two tertiary circuits are opposed and not coöperative as when used in receiving; thus there is no current flow or difference of potential in the bridge H^2 and no effect is produced upon the receiver to actuate the transmitter, resulting in an absence of reaction from local effects or retransmission and effecting a reproduction of the currents without interference. It will be manifest that a reversal in the transmission over the line circuits will produce automatic reciprocal effects in the twin repeaters; that there is no current induced into circuit L^2 when circuit L is the receiving side, and that no current will be induced into circuit L when L^2 is the receiving side. Hence it will be clear that several repeaters, dependent upon line circuit losses, of course, can be operated in series in a through circuit. Fig. 2 is an embodiment of the operative features of the invention, as shown in Fig. 1, with modified circuit details. The main circuit sections in this instance are shown physically separated as well as operatively distinct. The two tertiary circuits for each repeater are also physically separated as well as operatively distinct. The respective windings for the receivers are shown divided and one coil or helix apportioned to each pole. This is so shown merely for clearness, as the windings may be arranged to have a helix on each pole for each circuit. The induction coil windings in this view are reduced in number but should have equal and relative values for each circuit, as set forth in connection with Fig. 1. Each primary circuit is independent, having an individual battery or current supply. The operation is essentially the same as in the first arrangement and may be briefly described as follows: An initial current in section L^2 will flow inward, as designated by the arrows, by way of conductor W^3 through the secondary winding of induction coil C^3 , thence out by way of conductor W^4 . This current sets up induced local effects in the primary and tertiary circuits, the effects being similar to those explained above. The induced current in tertiary circuit P^3 is directly induced from the coil C^3 secondary,

while the induced current in tertiary circuit P^4 is a reinduced current, from the same source, into primary circuit B^3 . These tertiary currents flow as designated by the arrows and coöperate in operating receiver T^2 of repeater R^2 . The operation of repeater R^2 sets up a current from battery B^x in primary circuit B^2 , reproducing the originating currents with renewed power. The current in passing through the primary windings of induction coils C and C^5 induces the reproduced currents into the secondary windings of the coils, whence it is transmitted to the next repeater or terminal station. The inducing current in primary circuit B^2 also sets up a current in tertiary circuit P^2 through the tertiary winding of coil C , and a corresponding current is set up in tertiary circuit P through the secondary winding of coil C^5 . These induced currents in the tertiary circuits flow differentially to produce a neutral effect for the receiver, as in the arrangement shown in Fig. 1. In the modified arrangement the current flows in opposite directions through two coils of receiver T , which coils, being equal in inductive effect, produce the neutral or inert state by counter electro-magnetic action.

What I claim as new and desire to secure by Letters Patent is:

1. In a reciprocal telephonic repeating system, the combination of a divided main telephone circuit having independent induction coil secondary windings in each division, differentially controlled repeating devices, one device for each main circuit, divided local or tertiary circuits and a primary circuit for each main circuit, each repeating device being connected into its respective tertiary circuits and respectively associated inductively with its main circuit secondary windings, primary windings in each primary circuit associated with said secondary windings, a battery or current supply and a transmitter in each primary circuit, each transmitter being actuated from its respective main circuit and operating to transmit into the next associated circuit only, together with means within the tertiary circuits for rendering each repeating device operative by its respective inducing line currents and inoperative by the reproduced currents set up by the opposite or associated repeating device.

2. In a reciprocal telephone repeating system, the combination of a telephone-line comprising operatively independent circuit sections, secondary induction coil windings connected in each section, divided tertiary and primary windings and respective divided tertiary and primary circuits therefor inductively associated with their respective line sections, an independent repeating device for each line circuit section, each repeating device being connected in a respective tertiary circuit or tertiary circuit divisions,

which provide for differential current flows or equivalent neutralizing counter-action in the repeating devices to the reproduced currents, an auxiliary induction coil secondary 5 winding connected in one side or circuit of each divided tertiary circuit, and a primary to said winding being connected in the respective primary circuit with said main circuit primary windings, a battery or current 10 supply for each primary circuit and the transmitter of the opposite repeating device included in said primary circuit, whereby each repeating device is operated to repeat by the received induction currents from its 15 respective circuit section and retransmits the initial currents with renewed force into the next circuit section, and the opposite or reciprocating repeater device is not operated by such reproduced currents, thus preventing 20 self-reaction and securing unidirectional reciprocal retransmission.

3. In a telephonic repeating system, the combination of a telephone main circuit consisting of independent circuit sections, an 25 independent repeating relay for each section, the relays being controlled by both co-operating and opposing electro-magnetic actions, independent induction-coil secondary windings in each main circuit section, primary 30 and tertiary windings associated with said secondary windings for each relay, primary and tertiary circuits for said primary and tertiary windings, the respective tertiary windings being in their respective tertiary 35 circuits of each relay, a transmitter and a battery included in each primary circuit, the transmitter in each case controlling the outward currents in the opposite main and tertiary circuits, an auxiliary or balancing induction-coil, secondary winding for each 40 relay, the respective tertiary windings of the main circuit induction coils operating the respective relays by the induced inward currents from their respective circuit sections, 45 and the repeated or outward currents energizing said tertiary windings being opposed in their effect upon the receivers by the currents set up in the auxiliary induction coils, thereby producing a neutral effect and preventing 50 self reaction.

4. In a telephonic repeating system, the combination with a main line secondary circuit and a primary repeater circuit, of a repeating device, two local or tertiary circuits, each connected with the repeating device, one of said local or tertiary circuits being directly inductively connected with the main line secondary circuit and with the primary repeater circuit, and the other local 55 or tertiary circuit being directly inductively connected with the primary repeater circuit only.

5. In a telephone repeating system, the combination with a main line circuit and 60 repeater local circuits, of a repeating pri-

mary circuit containing a battery and a transmitter and also containing separate primary induction-coil windings, one of said windings being inductively connected with one of said repeater local circuits only and another of said windings being inductively connected with another of said repeater local circuits and with the main line circuit. 70

6. In a telephone repeater system, the combination with a line circuit and a primary circuit, of a repeating device having two windings, one of said windings being inductively connected with said line and primary circuits and the other of said windings being inductively connected with the 80 said primary circuit only. 75

7. In a telephone repeater system, the combination with a line circuit, two local circuits and a primary circuit, of a repeating device associated with said local circuits 85 for controlling the repeater, one local circuit being inductively connected with the line circuit and the primary circuit, and the other local circuit being inductively connected with the same primary circuit only. 90

8. In a telephone repeater system, the combination with a line circuit, two local circuits and a primary circuit, of two repeating devices one of which is associated with said local circuits, one of the local circuits being inductively connected with the line and primary circuit from the other repeating device, and the second local circuit being inductively connected with said primary circuit, the transmitter of the first 100 mentioned repeating device being connected in circuit with the primary of said last-mentioned repeating device. 100

9. In a telephone repeating system, the combination of a telephone line and relays, 105 said line being divided into independent circuit sections by relay stations, two relays at each relay station, one for each circuit section, two local or tertiary circuits for each relay, in which tertiary circuits received induced currents from the line circuit section co-operate to actuate their respective transmitters, a primary circuit associated with each relay transmitter, each primary circuit being in inductive connection with the opposite line circuit section and with both opposite tertiary circuits, the actuation of either transmitter inducing currents into the opposite line section and also inducing currents in each of the opposite tertiary 115 circuits, which transmitter currents in the opposite tertiary circuits set up opposing electro-magnetic effects in the relay receivers and prevent reoperation and self-action. 120

10. In a telephone repeating system, the combination of a repeating device, two local circuits with which the repeating device is connected, a main line circuit and a primary circuit, one of the local circuits being 130

inductively connected with the line circuit and the other local circuit being inductively connected with the primary circuit.

11. In a telephone repeater system, the combination with a main telephone circuit and a primary circuit therefor, of a repeating device and two local circuits associated with and controlling the repeating device, one of said local circuits being inductively connected with the main telephone circuit and its primary circuit, and the other local circuit being inductively connected with said primary circuit only, each inductive connection being the inductive equivalent of the other in inductive effect upon the repeater from outward currents.

12. In a telephone repeater system, the combination of a divided or sectional main circuit, two repeating devices at a station on said main circuit, a divided or double tertiary circuit for each repeating device, an auxiliary induction coil secondary winding in one division of each double tertiary circuit, a primary circuit and a battery associated with each repeating device transmitter, each primary circuit being inductively associated with the main circuit division opposite to its repeating device and also with the respective tertiary circuits.

13. In a telephone repeating system, the combination of a main line circuit divided at a repeater station into two independent circuit sections, an independent repeater-receiver for each circuit section at the repeater station, two local or tertiary circuits for each repeater-receiver, forming an electrical or induction balance therefor, an independent primary circuit for each main line circuit section, having a source of energy and a transmitter, and an induction coil for each main line circuit section, said coils having primary, secondary, and tertiary windings for directly inductively associating each repeater receiver in its tertiary circuit with its respective main line circuit section and with the primary circuit of the opposite repeater.

14. In a telephonic repeating system, the combination of a main line divided into two independent circuit sections at a repeater station, a repeating device for each main line section at the repeater station, two tertiary circuits for each repeater device, a primary circuit for each repeater device, each of the main circuit sections and its respective primary circuit being inductively connected with one of their respective tertiary circuits, the other tertiary circuits being respectively inductively connected each with their respective primary circuits.

15. In a telephone repeater system, the combination of a main circuit section, tertiary circuits, a primary circuit and a repeating device, induction coil windings as-

sociating said main circuit sections, a tertiary circuit, the primary circuit, and the repeating device, the induction coil secondary winding inducing the inward currents from the line circuit into their associated tertiary circuit and the primary circuit simultaneously, an induction coil associating said primary circuit, a second tertiary circuit and the repeating device, the current induced into said primary circuit being reinduced into the second tertiary circuit by means of said last-mentioned induction coil, the currents in the two tertiary circuits coöperating in setting up the electro-magnetic effects for the repeater-receiver to actuate said receiver.

16. In a telephone repeater system, the combination of a main circuit section, tertiary circuits, a primary circuit and a repeating device, induction coil windings associating said main circuit section, a tertiary circuit, the primary circuit and the repeating device, an induction coil associating said primary circuit, a second tertiary circuit and the repeating device, the local currents in said primary circuit simultaneously inducing currents into the line circuit and into each of the tertiary circuits to set up in the tertiary circuits opposing electro-magnetic effects, and to set up or inductively transmit into the line circuit the reproduced currents, the opposing electro-magnetic effects rendering the repeating device inactive.

17. In a twin telephone repeater, the combination of two independent line circuits, a repeating device for each line circuit each comprising a receiver and a transmitter, a primary circuit for each line circuit and its repeater, each primary circuit being directly inductively connected with its respective line circuit but controlled by and connected with the transmitter of the opposite repeating device, two local or tertiary circuits for each repeating device, one of which tertiary circuits of each repeating device is directly inductively connected with its respective line circuit and also with its respective primary circuit, the other tertiary circuit of each repeating device being directly but separately inductively connected with its respective primary circuit.

18. In a telephonic repeater, in combination, two independent line circuits associated for repeater service, two repeating devices, one for each respective line-circuit, each repeating device comprising a receiver and a transmitter, a winding in each line-circuit to control the respective repeating devices to actuate them by the inward or received currents, a transmitting or primary circuit for each repeating device, a balancing auxiliary or tertiary-circuit for each repeating device, divided circuit neutralizing means in each balancing circuit for each repeating device, one division of each neutralizing means being directly inductively connected with its

respective line-circuit and with the transmitting or primary-circuit of the opposite repeating device, and the other division of each neutralizing means being directly inductively connected with the transmitting or primary-circuit only of the opposite repeating device.

19. In a reciprocal telephone repeating system, the combination, with twin repeaters at a repeating station in a main line circuit for the repeating of telephone transmission, of circuits and apparatus, as follows: twin line-circuits, one for each repeater, twin primary circuits, one for each repeater-transmitter, each primary circuit being inductively associated only and directly with the opposite line-circuit and its repeater apparatus, two triple circuit induction-coils for such respective collective and immediate inductive association of circuits, twin local or tertiary circuits for each of the twin repeaters, by which twin circuits respectively the repeaters are rendered inert to their repeated currents, two double circuit induction coils, one for each of the twin tertiary circuits, each double circuit induction-coil directly inductively associating one of its respective tertiary circuits with a respective primary circuit for coöperation in rendering the respective repeater inert to the repeated or outward currents, and also rendering it increasingly efficient to received or inward line currents, the other of the respective tertiary circuits forming the direct inductive association of the receiver of its respective repeater with its respective line-circuit and with the associated primary circuit through the respective triple-circuit induction-coil, as and for the purpose set forth.
20. In a reciprocal telephone repeater system, the combination with two telephone lines of two electro-magnetic receivers connected inductively one with and for each of said lines, and two variable resistance transmitters operated by said receivers and connected inductively one with and for each of said lines, a primary or transmitting circuit for each of said transmitters, tertiary local circuits for each receiver and means within the tertiary circuits for neutralizing each receiver to prevent automatic reaction between the lines by repeated currents, and means for establishing all the said inductive connections for the receivers and transmitters directly and immediately with their respective lines.
21. In a reciprocal telephone repeater system, the combination with two line circuits, of a repeater for each, a primary or reproducing circuit and two tertiary or receiving circuits for each repeater, one tertiary circuit of each repeater inductively directly connecting the repeater with both its respective line circuit and the primary circuit of the other or associated repeater, and the

other tertiary circuit of each repeater being individually directly inductively connected also with the primary circuit of the other or associated repeater.

22. In a telephone-current repeating and renewing system, the combination with a sectionally divided main telephone-circuit having terminal telephones, of one or more repeater stations on said circuit, two repeaters for reciprocal coöperation at each station, one repeater for each respective circuit, each repeater having its receiver operatively identified with but one respective line-circuit, and a current renewing local battery-circuit for each repeater-transmitter, said circuit being directly and immediately inductively associated with the next main circuit-section to transmit into but that one of the two circuit-sections, local receiver-circuits which jointly act coöperatively at times for receiving, and at times differentially to prevent operation, for each repeater, and means for directly inductively associating each repeater-circuit with its respective main circuit-section.

23. In an automatically reciprocal telephone current reinforcer or repeater system, the combination with a line or main circuit which is separated or divided into repeating sections, of one or more repeating stations on said main circuit, with two repeaters at each station, each repeater comprising a sensitized or polarized electro-magnetic receiver and a variable-resistance transmitter, the transmitters being adapted to be actuated by their receivers by the received line-currents and to transmit their reproduced currents into the main circuit section succeeding their respective receiver's sections, the two transmitters at any one station each being adapted to transmit in an opposite direction to the other, also of two local circuits for each receiver in which the receivers are connected in a manner to be balanced and neutral or inert to the local repeating currents, a line induction coil with secondary, tertiary and primary windings for each line section or repeater at each station, each such coil having its secondary in the line, its tertiary in one of the balancing local circuits of each repeater and its primary winding in circuit with the transmitter of the opposite repeater-transmitter and a source of current, another induction-coil for each repeater, said coils having secondary and primary windings, with their secondary windings in the circuit of the other balancing local-circuit respectively and the primary windings also in the circuit with the respective opposite transmitter and its source of energy.

24. In a reciprocal telephone current-repeating and renewing system, the combination with two line circuits, of two telephone repeaters, each comprising a magnetically sensitized electro-magnetic receiver and a

variable-resistance transmitter in repeater relation, each repeater having its receiver operatively identified for receiving with only one line circuit respectively and having its transmitter operatively identified for retransmission with only the other or opposite line circuit, a pair of tertiary circuits for each repeater adapted respectively to cooperate in received current effects to render the receivers sensitive to the inward line currents, a pair of primary circuits, one for each transmitter, means for directly inductively connecting each primary circuit with the opposite line circuit and one of the tertiary cir-

cuits of the opposite repeater, and means for 15 individually directly inductively connecting each primary circuit also with the second tertiary circuit of the opposite repeater, and the primary repeated current flows being adapted to produce differential effects in the 20 separate inductive connections to thereby render the repeaters insensitive, and effecting unidirectional reciprocal re-transmission in the lines.
